UNITED STATES PATENT OFFICE.

BRIGHAM BALLANTYNE, OF SUMPTER, OREGON.

AUTOMATIC CIRCUIT-BREAKER.

SPECIFICATION forming part of Letters Patent No. 704,496, dated July 15, 1902.

Application filed August 8, 1900. Serial No. 26,271. (No model.)

To all whom it may concern:

Be it known that I, BRIGHAM BALLANTYNE, a citizen of the United States, residing at Sumpter, Baker county, Oregon, have invented certain new and useful Improvements in Automatic Circuit-Breakers, of which the following is a specification.

My invention relates to improvements in automatic circuit-breakers; and the object of the invention is to provide an exceedingly simple arrangement which will guard against the effects of dangerous excesses of current, while at the same time providing means whereby the circuit shall be restored to normal condition immediately upon the current being reduced.

The invention is illustrated in the accompanying drawing, in which the figure is a side elevation of the switch and operating-magnets with the line-wires shown diagrammatically.

Referring to the drawing by reference-letters, a' and a^2 represent the line-wires of an electric circuit, including, for instance, a series of lamps B.

H represents a switch-lever pivoted at I and having a contact c' co-operating with a stationary contact c^2 , the switch formed thereby being representative of any well-known form of switch—such, for instance, as spring-copper brush, carbon-point breaks, mercury-cup contacts, or the like. To the opposite end of the switch-lever are secured the cores N' N² of two solenoids m' m², the solenoid m² being wound with coarse wire in such a manner that the ordinary current flowing therethrough does not magnetize it sufficiently to overcome the tension placed upon the lever either by the adjustable weight F or the spring E, or both.

The line-wire a^2 is connected with the coil of the solenoid m², the connection being then by wire a³ to switch point or contact c' , whence it passes by switch-piece c² to the lamps or other point of distribution.

The solenoid m' is arranged in a shunt-circuit around the switch, being connected by wire a⁴ with wire a² and by wire a⁵ with the line-wire. This solenoid m' is wound with fine wire to produce a resistance sufficient to prevent effective current at the normal strength passing therethrough.

In case of a dangerous excess of current on the wires, therefore, it will be seen that solenoid m² will be sufficiently energized to oper-

ate the switch-lever to break the circuit at c' 55 and the entire current will be turned through the high-resistance coil, thereby energizing the same strongly and holding the switch-lever in its open position, the high-resistance coil, however, being wound for a 60 sufficiently high voltage to prevent the current injuring the coil itself. The parts will, however, be maintained in this position until the current is restored to its normal condition or completely cut off, when the spring or 65 weight will immediately restore the switch-lever to normal position.

Having thus described my invention, what I claim is—

1. In an automatic circuit-breaker, the combination with the conductors a' and a^2 , of a stationary contact c^2 , connected with said conductor a' , a pivoted switch-lever having a contact c' normally in engagement with said stationary contact, a solenoid of low resistance electrically connected with said movable contact and with the conductor a^2 , a core for said solenoid connected directly to said lever for positively operating the same to separate the contacts on the presence of an excess of current in the solenoid-coils, an independent solenoid of high resistance, a core therefor connected directly to said lever, said high-resistance solenoid-coil being in closed circuit with said conductors a' and a^2 , substantially 75 as described.

2. In combination with the main conductors a' and a^2 , a stationary contact c^2 connected to said conductor a' , a centrally-pivoted switch-lever carrying a contact c' on its 90 front end, means whereby said lever is held with the front end normally depressed, a pair of solenoids arranged beneath the rear end of the lever, one of said solenoids being of low resistance and the other of high resistance, 95 electrical connections from said low-resistance coil to the movable contact and to conductor a^2 , electrical connections from the high-resistance solenoid to the conductors a' and a^2 , and a core in each solenoid directly connected with the rear portion of the switch-lever, substantially as described.

In testimony whereof I affix my signature in presence of two witnesses.

BRIGHAM BALLANTYNE.
